ELECTRIC TRUCK FOR TRANSPORTING GOODS IN A PLANT

Sven Lars Mikael Pettersson, Goteborg, Sweden, assignor
to AB Volvo, Goteborg, Sweden

Filed Jan. 10, 1975, Ser. No. 540,161

Claims priority, application Sweden July 11, 1974

Term of patent 14 years

Int. Cl. D12—14

U.S. Cl. D12—1

FIG. 4

FIG. 5

FIG. 6

FIG. 1 is a front perspective view from above of an electric truck for transporting goods in a plant showing the design of the present invention;

FIG. 2 is a rear perspective view thereof from above;

FIG. 3 is a side perspective view thereof from above;

FIG. 4 is a bottom plan view thereof;

FIG. 5 is a side elevational view thereof; and

FIG. 6 is a top plan view thereof.

I claim:

The ornamental design for an electric truck for transporting goods in a plant, as shown.
